(57) **CLAIM**

The ornamental design of a bubble wand, substantially as shown and described.

DESCRIPTION

FIG. 1 is a perspective view showing the front and right side of the bubble wand;

FIG. 2 is a perspective view showing the rear and left side thereof;

FIG. 3 is a front elevation view thereof;

FIG. 4 is rear elevation view thereof;

FIG. 5 is an elevation view of the left side thereof;

FIG. 6 is an elevational view of the right side thereof;

FIG. 7 is a plan view of the top thereof; and,

FIG. 8 is a plan view of the bottom.

The broken lines depict portions of the bubble wand that form no part of the claimed design.

1 Claim, 6 Drawing Sheets
